Attorney

UNITED STATES PATENT OFFICE

JAMES T. LEITCH, OF ALLENtown, PENNSYLVANIA, ASSIGNOR OF ONE-FIFTH TO
TILGHMAN A. FREED AND ONE-FIFTH TO EVA S. FREED, BOTH OF ALLENtown,
PENNSYLVANIA.

PHONOGRAPH.

1,419,459.

Specification of Letters Patent. Patented June 13, 1922.

Original application filed August 12, 1920, Serial No. 403,115. Divided and this application filed April 15, 1921. Serial No. 461,615.

To all whom it may concern:

Be it known that I, JAMES T. LEITCH, a citizen of the United States of America, residing at Allentown, in the county of Leigh 5 and State of Pennsylvania, have invented certain new and useful Improvements in Phonographs, of which the following is a specification.

This invention relates to phonographs and 10 other like sound reproducing devices.

More especially the invention relates to the amplifying sound box for phonographs.

One important object of the invention is 15 to provide an improved general construction of devices of this character.

A second important object of the invention is to provide an improved diaphragm for such sound boxes by the use of which the most sensitive sounds will be properly re- 20 produced and the sensitive overtone waves properly blended so as to avoid harshness and the so called "blasting."

A third important object of the invention is the provision of a sound box having a 25 resonator of novel construction whereby increased amplitude of vibration of the sound waves will be obtained and the absorption and consequent waste of sound producing vibrations be eliminated.

30 A fourth important object of the invention is to provide an improved arrangement of needle arm and its bracket or support therefor in order to prevent damping of vibrations by absorption in the body of the sound 35 box as well as to eliminate the production of metallic effects.

A fifth important object of the invention is the provision of a novel amplifier so connected with the resonator that the produced 40 vibrations will be collected and amplified.

With the above and other objects in view, the invention consists in general of certain novel details of construction and combinations of parts hereinafter fully described, 45 illustrated in the accompanying drawings, and specifically claimed.

In the accompanying drawings, like characters of reference indicate like parts in the several views, and:—

50 Fig. 1 is a face view of an amplifier con-

structed in accordance with this invention and showing its position relative to an ordinary sound box.

Fig. 2 is a detail section on the line II—II.

Fig. 3 is a perspective of part of a dia- 55 phragm.

In the drawing there is shown a sound box and amplifier particularly adapted for use in connection with the device shown in my mica copending application filed Au- 60 gust 12, 1920, and bearing the Serial No. 403,115 of which this application is a division.

The sound box shown in the copending application is illustrated in general, in the 65 present case, at 10. The bracket and connecting means also referred to in the above-mentioned application are shown respectively at 11 and 12.

The amplifier includes a casing 13 having 70 a beaded edge 14 wherein are rubber rings 15 against which rests the periphery of a mica diaphragm 16. On the other side of this diaphragm is a rubber sleeve 17 against which rests a second mica diaphragm 18. 75

This second mica diaphragm is held in position by an angle ring 19 fitted within the casing 13. Thus the amplifier forms a closed box the ends of which are constituted by 80 mica diaphragms. It will be noted that the connector 12 is fixed to the diaphragm 16 as indicating at 20.

It is obvious that the case 12 is merely 85 typical of a suitable means for vibrating the diaphragm 16.

I preferably make one or both of these dia- phragms 16 and 18 of peculiar character, the diaphragm thus constructed, being formed from a thin sheet of mica having its surface covered by a multitude of fine particles of 90 metal 21, the latter being held on the mica by some suitable adhesive so that the sur- face of the diaphragm appears as though powdered with metal. The effect of this metallized mica diaphragm is to render the 95 reproducer responsive to weak and sensitive sounds while at the same time the overtone waves are properly blended. Thus the re- production has all of the characteristics of the original sound without any harshness or 100

"blasting" being caused by improper or defective vibrations to the diaphragm.

There has thus been provided a simple and efficient device of the kind described and for 5 the purpose specified.

It is obvious that minor changes may be made in the form and construction of the invention without departing from the material principles thereof. It is not therefore 10 desired to confine the invention to the exact form herein shown and described, but it is

wished to include all such as properly come within the scope claimed.

Having thus described the invention, what 15 is claimed as new, is:—

In a phonographic reproducer, a diaphragm consisting of a mica disc having a multitude of metallic particles adhesively connected to its surface.

In testimony whereof I affix my signature.

JAMES T. LEITCH.
